UNITED STATES PATENT OFFICE

2,275,757

CRANKPIN GRINDER

Edward S. Hanson, Jr., Zion, Ill.

Application June 9, 1941, Serial No. 397,295

5 Claims. (Cl. 51—241)

This invention aims to provide a novel structure for grinding the pin of the crank shaft of an engine, preferably an internal combustion engine, the construction being such that much of the engine structure will come into play during the grinding operation, it being necessary to supply no more than a simple mechanism, supplemental to the engine parts, to bring about a grinding operation.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in transverse section, a device embodying the invention, most parts being in elevation;

Fig. 2 is an elevation wherein the parts are viewed at right angles to the showing of Fig. 1;

Fig. 3 is a section on the line 3—3 of Fig. 2;

Fig. 4 is an elevation showing one of the nuts, parts being sectioned away;

Fig. 5 is a sectional view showing the device in use on an internal combustion engine of the V-type;

Fig. 6 is a top plan of the structure delineated in Fig. 5.

The numeral 1 marks a crank pin, preferably forming part of an internal combustion engine. The crank shaft disks are shown at 2. The numeral 3 marks a fixed bearing on a pitman 4, the bearing cooperating with the crank pin 1. The pitman 4 is pivoted, as indicated at 5a in Fig. 5, to an engine piston 6a, mounted to reciprocate in an engine cylinder 1a.

Bolts 8 and their nuts 9 are used to hold assembled with the fixed bearing 3 and with the crank pin 1, a removable bearing (not shown), complementary to the bearing 3 and cooperating with that bearing to receive the crank pin 1, when the engine is in working condition. When the grinding operation is to take place, the aforesaid complementary bearing (not shown) is removed, and its place is taken by spacers 10 on the bolts 8. Spring plates 11 are placed on the

bolts 8 and are held in abutment with the spacers 10 by one of the nuts 9, and a specially constructed nut 12. The spring plates 11 hold the crank pin 1 seated in the bearing 3.

5 The nut 12 has a spindle 14, provided with a transverse shoulder 15 of any desired construction. A nut 16 is threaded on the lower part of the spindle 14 and is held against rotation, backwardly, by a lock washer 17.

10 The machine includes a frame, denoted as a whole by the numeral 18, the frame including a tubular bearing 19, disposed parallel to the spindle 14, the bearing having transverse, outstanding arms 20 and 21, mounted to swing on the spindle, the arm 21 abutting against the lock washer 17, which is retained by the nut 16. A coiled spring 22 surrounds the spindle 14, and abuts at its upper end against the shoulder 15 on the spindle, the spring abutting at its lower end against the arm 21.

15 The machine includes a frame, denoted as a whole by the numeral 18, the frame including a tubular bearing 19, disposed parallel to the spindle 14, the bearing having transverse, outstanding arms 20 and 21, mounted to swing on the spindle, the arm 21 abutting against the lock washer 17, which is retained by the nut 16. A coiled spring 22 surrounds the spindle 14, and abuts at its upper end against the shoulder 15 on the spindle, the spring abutting at its lower end against the arm 21.

20 A grinding mechanism is provided, and includes a motor 23 secured to the lower end of the bearing member 19 of the frame 18. A shaft 24 is mounted to rotate in the bearing 19, and is connected to the shaft 25 of the motor 23 by a coupling 26. A grinding wheel 27 is secured to the upper end of the shaft 24 and engages the crank pin 1.

25 When the parts are assembled as shown in Fig. 1, the frame 18 is swung lengthwise of the crank pin 1, on the spindle 14 of the nut 12, the motor 23, the shaft 25, the coupling 26 and the shaft 24 impart rotation to the grinding wheel 27, and the irregularities on the crank pin 1 are ground away when the crank pin is caused to move in an orbit. If the device is used on an automobile, the after end of the automobile may be jacked up, and the crank pin 1 be caused to move in an orbit by turning manually, the rear wheels of the automobile.

30 The position of the grinding wheel 27, relatively to the crank pin 1, is attained by manipulating the nut 16. The function of the spring 22 is to hold the arm 21 of the frame 18 down on the washer 17 when the grinding wheel 27 moves over a low place in the crank pin 1.

35 In Figs. 5 and 6, parts hereinbefore described have been designated by numerals already used, with the suffix "a." Figures 5 and 6 show that the device is useful in connection with a motor of the V-type, as well as with a motor the cylinders of which are disposed vertically above the crank shaft.

40 Having thus described the invention, what is claimed is:

1. A crank pin grinder comprising an engine cylinder, a piston slidably mounted in the cylinder, a pitman pivoted to the piston and provided with a fixed bearing shaped to receive a crank pin, a bolt carried by the fixed bearing and forming part of means for assembling a complementary, removable bearing assembled with the fixed bearing and with a crank pin, a nut threaded on the bolt and having a spindle, a frame mounted on the spindle, and grinding mechanism carried by the frame and so located as to engage a crank pin mounted in the bearings.

2. A crank pin grinder constructed as set forth in claim 1, and wherein the frame is mounted to swing on the spindle, to carry the grinding mechanism lengthwise of a crank pin mounted in the bearings.

3. A crank pin grinder constructed as set forth in claim 1, in combination with a spacer on the bolt, and a spring on the bolt, between the spacer and the nut, the spring exerting pressure in the direction of the fixed bearing, on a crank pin mounted in the bearings.

4. A crank pin grinder constructed as set forth in claim 1, and wherein the frame is mounted to swing on the spindle, lengthwise of a crank pin which is mounted as aforesaid, and to move for adjustment longitudinally of the spindle, to bring the grinding mechanism into engagement with a crank pin which is so mounted, means under the control of an operator and carried by the spindle and cooperating with the frame to advance the grinding mechanism into engagement with a crank pin which is so mounted, and spring means engaged with the frame and with the spindle to hold the frame engaged with the means under the control of an operator.

5. A device of the class described, constructed as set forth in claim 1, and wherein the grinding mechanism comprises a shaft supported for rotation on the frame, a motor carried by the frame and engaged with one end of the shaft, and a grinding wheel mounted on the opposite end of the shaft.

EDWARD S. HANSON, JR.
